CLAIM

The ornamental design for a machine for processing animal feed, as shown and described.

DESCRIPTION

FIG. 1 is a front elevational view of a machine for processing animal feed showing my new design.

FIG. 2 is a rear elevational view thereof.

FIG. 3 is a right side elevational view thereof.

FIG. 4 is a left side elevational view thereof.

FIG. 5 is a top plan view thereof; and,

FIG. 6 is a bottom plan view thereof.

(Continued)

The broken lines in the figures depict portions of the machine for processing animal feed which form no part of the claimed design.
